CONTAINER-TAB MARKING MACHINE

John M. Hothersall, Brooklyn, N. Y., and August E. Almgren, Hillside, N. J., assignors to American Can Company, New York, N. Y., a corporation of New Jersey

Original application November 5, 1937, Serial No. 173,050. Divided and this application December 4, 1941, Serial No. 421,672

11 Claims. (Cl. 101—11)

The present invention relates to a container or can treating machine and has particular reference to devices for imprinting a desired mark on a predetermined portion of a container. This is a division of our parent application Serial Number 173,050, filed November 5, 1937, now Patent No. 2,284,660, issued June 2, 1942.

An object of the present invention is the provision of a can treating machine for preparing a closed but empty milk can with a carrying tab for subsequent filling, by individually feeding the empty cans from a suitable source of supply, shifting the carrying tab into a predetermined position, stamping a desired insignia on the positioned tab, and delivering the marked can into position for filling, all of the operations being correlated to produce the desired results.

Numerous other objects and advantages of the invention will be apparent as it is better understood from the following description, which, taken in connection with the accompanying drawings, discloses a preferred embodiment thereof.

Referring to the drawings:

Figure 1 is a top plan view, with parts broken away, of a can treating machine embodying the instant invention, the view also showing a portion of a can filling machine;

Fig. 2 is an enlarged top plan view of a can showing the desired marking on the carrying tab of the can;

Fig. 3 is a longitudinal section taken substantially along the broken line 3—3 in Fig. 1, with parts broken away;

Fig. 4 is a sectional detail taken substantially along the horizontal broken line 4—4 in Fig. 3, with parts broken away;

Fig. 5 is a transverse section of the upper portion of the machine, the section being taken substantially along the broken line 5—5 in Fig. 1;

Fig. 6 is a sectional detail taken substantially along the horizontal line 6—6 in Fig. 5, with parts broken away;

Fig. 7 is an enlarged transverse vertical section of a tab marking portion of the machine, the view being taken substantially along the broken line 7—7 in Fig. 1, with parts broken away, a can also being shown in place in the machine;

Fig. 8 is an enlarged fragmentary top plan view of a can carrying tab lifting device, the view being turned through 180 degrees from that shown in Fig. 1 and also showing a can in place in the device;

Figs. 9, 10 and 11 are longitudinal sections

taken substantially along the line 9—9 in Fig. 8, the sections showing the various parts in different positions relative to the upper end of a can, portions of the can in Figs. 10 and 11 being broken back and shown in section;

Figs. 12 and 13 are sectional views of the upper end of a can showing its tab being lifted, the views being taken substantially along the line 12—12 in Fig. 8;

Figs. 14 and 15 are sectional details of the tab marker as viewed substantially along the respective horizontal lines 14—14, and 15—15 in Fig. 7, Fig. 14 also showing cans being operated upon;

Figs. 16 and 17 are sectional details of the tab marker taken substantially along the respective vertical lines 16—16, and 17—17 in Fig. 7, Fig. 17 also showing a can in place in the machine; and

Fig. 18 is an enlarged perspective view of a part of the tab marker.

An exemplary form of can which is adapted to be treated and prepared for filling in the machine illustrated in the drawings is fully disclosed in United States Patent 2,085,070, issued July 6, 1937, to John M. Hothersall. Such a can is herein indicated by the letter *b* (Fig. 2). The can is preferably made of fibre and is provided with fibre top and bottom end members. The top end member is formed with a filling and dispensing opening *c* which is disposed at one corner of the can. This opening is adapted to be subsequently closed and sealed, after the can is filled, by a flap or closure element *d* which is hingedly secured to the top end member.

The closure element is provided with a plug section *e* formed to fit into and fill the opening *c* when the closure element is in can closing position. This closure element is formed integrally with a can lifting or carrying tab *f* the whole being secured by a staple *g* to the top end member of the can. The staple is disposed between the closure element and the tab so that they may be hinged upwardly independently.

The cans *b* to be treated in the machine have been preferably sterilized and coated interiorly and exteriorly with a suitable liquid proof, air impervious coating. The filling and dispensing opening *c* has also been closed hermetically by the closure element *d* and the can is in sterile condition. The carrying tab *f* lies flat against the top end member.

The cans *b* to be marked are received from any suitable source of supply in an upright posi-

tion with the closure element *d* at the top of the can. The cans are deposited in the path of travel of a pusher *F* (Fig. 1) which is located adjacent a tab raising element *G*. The pusher advances the can past the tab raising element and places it into a rotatable turret *H*. This movement past the tab raising element effects a raising or hinging of the tab *f* of the can so that it assumes an inclined position relative to the can end member instead of lying flat against it.

Now the can is carried intermittently by the turret *H* through a circular path of travel. During this travel the raised tab *f* is engaged by a marking mechanism *J* and is dated. The can is advanced into another position where the closure element *d* is lifted by a closure element lifting device and suction cup *K*. This opens or uncovers the filling opening *c*. The opened closure element now is held open while the can is advanced further to a transfer device *M* which removes it from the turret *H* and places it into a filling machine *N*. The closure element opening device *K* and the filling machine *N* form no part of the instant invention and therefore will be only briefly mentioned.

A can *b* to be marked is placed in any suitable manner in an upright position on a table *21* (Figs. 1 and 5) secured to a frame *22* which constitutes the main frame of the machine. The can resting on this table is directly in front of the pusher *F* and is alongside of and below the tab raising element *G*. Placing of the can in this position adjacent the tab raising element *G* actuates the element and shifts it into operating position against the top of the can. Therefore the tab raising element mechanism will be explained before describing any further movement of the can by the pusher *F*.

The tab raising element *G* (Figs. 1, 8, 9, 10 and 11) is supported on a pivot pin *24* carried in lugs *25* formed on an upright stop plate *26* of the table *21*. A free end *27* of the element is formed with a wedge shaped blade *28* (see also Figs. 12 and 13). The opposite end of the element carries a long rod *29* and the outer end of this rod is held under tension by a spring *31*. This is the normally raised position as best shown in Fig. 9.

The rod *29* rests against the outer end of a double acting spring barrel *34* comprising a small barrel *35* fitting within a large barrel *36* and confining a compression spring *37* between and within them. The spring *37* is a little heavier and stronger than the spring *31*. The larger barrel *36* is disposed in a bore *38* formed in a boss *39* on the stop plate *26* and is retained against displacement from the bore by a pin *41* secured in the boss. The inner end of the pin extends into a slot *42* formed in the large barrel.

The small barrel extends in beyond the face of the stop plate *26* and is retained against displacement from the large barrel by a pin *44*. This pin is secured in the large barrel and operates in a slot *45* formed in the small barrel. This construction permits independent sliding movement of the barrels and uses the one spring common to both.

A can moving toward the tab raising element *G* while being placed on the table *21* engages against the protruding end of the small barrel *35* and pushes the double spring barrel *34* outwardly in its bore *45* and hence swings the rod *29* outwardly against the pull of its tension spring *31*. This action rocks the tab raising element *G* on its pivot pin *24* and brings its wedge shaped

blade *28* down on top of the can end in a position adjacent the can carrying tab *f*, as best shown in Figs. 8 and 10. The large barrel *36* thereupon is blocked against further movement and the small barrel *35* slides into it, compressing the spring *37* as the can continues to advance into the position of Fig. 11.

This advancement of the can terminates when it strikes the stop plate *26*. The can is now directly in front of the pusher *F* and it is this pusher that next operates to advance the can into the turret *H*, as hereinbefore mentioned.

The can pusher *F* (Figs. 1 and 5) is mounted in a guideway *48* in the main frame of the machine and reciprocates transversely of the machine. The pusher is propelled by a link *49* which connects the pusher with the upper end of an arm *51* mounted on a rocker shaft *52* carried in a bracket *53* depending from the machine frame *22*. The lower end of another arm *55* also mounted on the rocker shaft carries a cam roller *56* which operates in a cam track *57* formed in a compound cam *58* on a cam shaft *59* journaled in spaced bearings *61* formed in the machine frame.

One end of the cam shaft *59* carries a bevel gear *62* which meshes with and is driven by a bevel gear *63* on a main driving shaft *64* journaled in a pair of spaced bearings *65* formed in the machine frame. The driving shaft is the main shaft of the machine and may be rotated in any suitable manner.

Thus on the forward stroke of the can pusher *F*, it engages the can *b* and pushes it forward, this being transversely of the machine. The can is guided by and slides along the stop plate *26*. During this transverse advancement of the can the wedge shaped blade *28* of the tab raising element *G* still seated against the top end member of the can, digs under the outer edge of the can-carrying tab *f* and lifts it into an inclined position, as best shown in Fig. 13.

Continued forward movement of the can pusher *F* delivers the can into a positioned turret *45* pocket *66* (Fig. 1) of the turret *H*. There are a plurality of such pockets formed in the turret. This turret is disposed adjacent the forward end of travel of the cam pusher *F* and comprises spaced upper and lower turret discs *67* formed integrally with a central hub *68* (see Fig. 7).

The turret hub *68* is secured on a vertical turret shaft *69* (Figs. 1 and 3) which is carried at its upper end in a bearing *71* in a projecting bracket section *72* of the machine frame. At its lower end the turret shaft is carried in a bearing *73* formed in a wall section *74* (Figs. 3 and 7) of the machine frame. The lower end of the turret shaft extends down below the bearing *73* and carries a geneva disc *75* having a plurality of spaced cam rollers *76* mounted thereon.

The rollers *76* (see Fig. 4) are arranged in a circle adjacent the periphery of the disc *75* and are successively engaged by a cam track *78* (Fig. 3) of a geneva cam *79* mounted on the continuously rotating drive shaft *64*. There is one cam roller *76* for each pocket *66* of the turret *H* so that as the rotating geneva cam *79* engages a cam roller the turret shaft *69* is revolved through a partial rotation. In this manner the turret is intermittently rotated to bring a pocket *66* into alignment with the can pusher *F* so that a can may be received therein.

A can received in a pocket of the turret is carried along a circular path of travel through several operating stations as hereinbefore men-

tioned. During this travel of the can it is supported on the table 21 and is retained in its pocket by a curved guide rail 81 (Figs. 1, 3, 5, 7 and 14) which is secured to the table. The extended end of the table is bolted to a flange 82 which is formed on the turret shaft lower bearing 73.

The first step rotation of the turret H brings the can b into alignment with the marking mechanism J. The marking mechanism includes a movable hollow arm 85 (Figs. 1, 5, 7, 14 and 15) which is formed with a short hollow shaft or stem 86 (Fig. 16) carried in a pair of vertical spaced bearings 87 (Fig. 7) of a bracket 88 bolted to the machine frame adjacent the path of travel of the can.

The free end of the arm 85 is formed with a stationary wedge shaped jaw 89 having a smooth inclined face 91 (Fig. 17). This end of the arm also carries a movable marking jaw 92 (Fig. 18) which is disposed directly over the stationary jaw 89 and is mounted on a pivot stud 93 threaded into the arm.

The lower face of the marking jaw 92 is inclined for cooperation with the stationary jaw 89 and also carries suitable embossed characters 95 (Fig. 18) formed thereon. In the present instance this embossment preferably indicates a day of the week. The jaw is made readily detachable so that other jaws carrying other characters, such as other days of the week, may be placed easily in the marker. This provides a means of marking the can with the day of the week on which it was handled, although any other notation may be used if desired.

The upper or movable jaw 92 normally is held separated from the lower or stationary jaw 89 by a compression spring 97 (Fig. 17) which surrounds a pin 98 carried in lugs 99, 101 formed on the sides of the respective jaws.

The jaws 89, 92 are also preferably heated. For this purpose steam is circulated through the hollow arm 85 and the resulting heat is imparted to the jaws by radiation and conduction. The steam first is introduced into the arm shaft upper bearing 87 (Fig. 16) which is divided into a steam receiving chamber 105 and a steam discharge chamber 106. These chambers are set off by bearing partition elements 107. The steam enters the receiving chamber 105 by way of an inlet pipe 108 (see also Fig. 7) which is threaded into a cap 109 bolted on top of the bearing 87. This steam pipe leads from any suitable source of steam supply.

Steam passing into the receiving chamber 105 circulates through a bore 111 in the arm shaft 86, through the hollow arm 85 and returns through a bore 112 also formed in the arm shaft. The end of the bore 112 is plugged and return steam escapes into the discharge chamber 106 through a hole 113 formed in the side of the shaft adjacent the closed end of the bore 112.

From the discharge chamber 106 the steam is exhausted to any suitable place of discharge by way of a plurality of holes 114 (Figs. 15 and 16) formed in the discharge chamber partition. These holes communicate with a clearance space 115 formed in the bearing 87. Steam from this space escapes by way of a hole 116 formed in the side of the bearing and by way of an outlet pipe 117 which is threaded into the bearing.

The steam heated arm 85 periodically is rocked on the arm shaft 86 as an axis to bring the marking jaw 92 and its cooperating stationary jaw 89 into can marking position. This is effected by an

arm 121 (Figs. 1, 5, 7, 15 and 16) which is keyed to the arm shaft 86 and which is disposed between the spaced bearings 87. A setscrew 120 threaded into this arm engages against the shaft and thus retains it in its bearings.

The arm 121 is connected by a link 122 to a similar arm 123 mounted on the upper end of a vertical shaft 124 carried in bearings 125 formed in the machine frame. On its lower end the shaft carries an arm 126 having a cam roller 127 which operates in a cam groove 128 of a multiple groove cam 129 mounted on the continuously rotating drive shaft 64.

As a can b in its pocket 66 of the intermittently rotated turret H comes into position under the marking mechanism J the steam heated arm 85 swings from its normal position (shown in dotted lines in Fig. 14) into the full line position shown in that figure. This swinging movement of the arm is brought about by the cam 129 and the normally separated jaws 89, 92 carried on the arm pass on either side of the raised tab f of the can, the lower or stationary jaw 89 reaching a position under the tab, while the upper or movable jaw is positioned above the tab. While the jaws are thus positioned, the upper jaw is forced down against the tab and the heated embossment 95 on the jaw face is impressed deeply therein. The lower jaw 89 acts as an anvil and supports the tab while under this pressure.

This embossing action is brought about by a toggle device which includes a pressure head 131 (Figs. 7 and 17). The head slides in the lower portion of a vertical guide 132 formed as part of the bracket 88. A pressure regulator member 133 is disposed in the upper portion of the guide. This member is formed with a stem 134 which extends up through the top of the guide and is provided with locknuts 135 for yieldingly holding the latter in place. A compression spring 136 is interposed between the member and the top of the guide.

The pressure head 131 and the regulator member 133 each are provided with a pivot pin 138 and these effect a connection with a pair of toggle links 139. The inner ends of the links pivotally are joined with each other and with the inner end of a rod 141 (see also Figs. 1 and 3). The opposite end of the rod is secured to an arm 142 (see also Fig. 5) mounted on a vertical shaft 143. At its lower end the shaft 143 carries an arm 144 having a cam roller 145 which operates in a cam groove 146 of the multiple cam 129. Hence at the proper time the toggle device is actuated, effecting a forcing of the pressure head 131 down against the marking jaw 92 and exerting the required embossing pressure on the tab f.

During the marking operation the can b is held firmly in its turret pocket 66 by an angular clamping plate 151 (Figs. 7, 14 and 17) which is swung into position against a corner of the can just prior to the marking operation and which is again swung out of the way at the completion of the marking operation. This clamping plate is formed on the free end of a lever 152 which is carried on a depending stud 153 secured in a boss 154 projecting down from the top wall section of the machine frame. Lever 152 is also connected by a link 156 to a lever arm 157 secured on the vertical shaft 124. Thus as the shaft 124 is rocked to shift the steam heated arm 85 into place, it also swings the clamping plate 151 into position.

The marking operation is followed by the lifting of the can closure element d to uncover its

filling opening *c*. This is effected by the can closure element lifting device *K* (Fig. 1) which is located adjacent the marking mechanism *J*. This lifting device *K* includes a suction cup *161* formed on an arm extension *162* of a curved rack which is operated by a straight rack *163* in the same manner as disclosed in our parent application. This feature forms no part of the instant invention and therefore will not be further explained herein.

Movement of the suction cup lifts the closure element *d* into a vertical position. Upon the next rotation of the turret *H* the opened closure element is held open by a curved guide rail *165* which extends along the path of travel of the cans. This rail is secured to the bracket extension *72* of the main frame.

On successive step rotations of the turret *H*, the can is advanced through a plurality of idle stations and thence brought into position adjacent the transfer device *M*. This transfer device includes a pair of upper and lower arms *167, 168* (Figs. 1 and 7) which are disposed respectively above and below the turret *H*. The upper arm *167* is mounted on the lower end of a short pin *171* held in a bearing *172* formed on the bracket *72* of the machine frame. The lower arm *168* is mounted on the upper end of a pin *173* which is concentric with the pin *171* and which is carried in a bearing *174* formed in the can support table *21*.

The outer ends of the arms *167, 168* are formed with extended hubs *176* which are connected by a tie rod *177* which construction insures movement of the arms in unison. A transfer arm *178* is an integral part of each of these hubs. These transfer arms project inwardly at an angle to the arms *167, 168*. It is these transfer arms *178* which effect the transfer of the can when arms *178* are oscillated in unison with the arms *167, 168*.

The arms *167, 168, 178* are moved by a lever arm *181* which is carried on the lower arm pin *173*. A link *182* connects the lever arm *181* with a lever *183* which is mounted on a short vertical shaft *184* carried in a bearing *185* formed in the lower wall section *74* of the machine frame.

Shaft *184* also carries an arm *186* (see Fig. 5) which is connected by a link *187* (see also Fig. 6) to the outer end of a lever *188* mounted on a pivot pin *189* carried in a bearing *191*. The bearing depends from the top wall section of the machine frame. The inner end of the lever *188* carries a cam roller *192* which operates in a cam groove *193* formed in the compound cam *58* mounted on the rotating cam shaft *59*.

When the advanced can *b* comes to rest adjacent the transfer device *M*, the transfer arms *178* move in behind and engage the can and push it out of its pocket *66* of the turret *H*. The ends of the can guide rail *81* (Fig. 1), the closure element holding rail *165*, and a similar curved guide rail *194* bolted on top of the machine frame *22* are shaped for guiding the can from its pocket while holding its closure element *d* in upright position during the transfer.

The removed can *b* then may be disposed of in any desired manner. To indicate that it is still under control while being delivered, Fig. 1 shows the can being pushed forward into a pocket *195* of a rotating turret *196* forming a part of the filling or other can handling machine *N*. The can may be retained in the filler turret pocket by the curved guide rail *194* or in any other manner.

It is thought that the invention and many of its attendant advantages will be understood from

the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for treating containers having tabs for carrying the containers, the combination of feeding devices for advancing containers along a predetermined path of travel, a tab raising element adjacent said path of travel of the containers for arranging the container tabs in a predetermined position, and a marking mechanism adjacent said tab raising element for impressing a desired mark on the arranged tabs of the advancing containers.
2. In a machine for treating containers having tabs for carrying the containers, the combination of feeding devices for advancing containers along a predetermined path of travel, a tab raising element adjacent said path of travel of the containers for lifting the container tabs into a predetermined position, means actuated by the containers as they advance for bringing said tab raising element into operable position adjacent the tabs, and a marking mechanism adjacent said tab raising element for impressing a desired mark on the lifted tabs of the advancing containers.
3. In a machine for treating containers having carrying tabs, the combination of feeding devices for advancing containers along a predetermined path of travel, a tab raising element adjacent said path of travel of the containers for arranging the container tabs in a predetermined raised position, a date marking mechanism adjacent said tab raising element for impressing a desired date on the positioned tabs of the advancing containers, and means for holding the containers in predetermined position while being marked.
4. In a machine for treating containers having carrying tabs, the combination of feeding devices for advancing containers along a predetermined path of travel, a tab raising element adjacent said path of travel of the containers for arranging the container tab in a predetermined marking position, a pair of tab marking jaws, means operable in time with the advancement of the containers for bringing said marking jaws into position relative to the positioned tabs, and instrumentalities for closing said marking jaws on the tabs so that a desired mark will be impressed thereon.
5. In a machine for treating containers having carrying tabs, the combination of feeding devices for advancing containers along a predetermined path of travel, a tab raising element adjacent said path of travel of the containers for arranging the container tab in a predetermined position, a pair of tab marking jaws, devices for heating said marking jaws, means operable in time with the advancement of the containers for bringing said heated marking jaws into position relative to the positioned tabs, and instrumentalities for closing said heated marking jaws on the tabs so that a desired mark will be impressed thereon.
6. In a machine for treating containers having carrying tabs lying flat against a wall of the containers, the combination of a sharp edged blade movable into place against a wall of a container and adjacent its carrying tab for insertion

between the container wall and the tab, means for actuating the inserted blade to lift the tab into an angular position relative to the container wall, and a marking mechanism adjacent said blade for impressing a desired mark on the raised tab.

7. In a machine for treating containers having carrying tabs lying flat against a wall of the containers, the combination of a sharp edged blade movable into place against a wall of a container and adjacent its carrying tab for insertion between the container wall and the tab, means operable by said container for actuating the inserted blade to lift the tab into an angular position relative to the container wall, and a marking mechanism adjacent said blade, said marking mechanism including a pair of pivoted jaws engageable on both sides of the raised tab for impressing a desired mark on the raised tab.

8. In a machine for treating containers having carrying tabs, the combination of a tab raising element for arranging a tab into a predetermined raised position on the container, a marking mechanism adjacent said tab raising element and including a fixed anvil jaw and a movable marking jaw mounted adjacent said fixed jaw and readily detachable for replacement with other jaws having other markings for impressing a desired mark on the raised tab of the container.

9. In a machine for treating containers having carrying tabs, the combination of a tab raising element for arranging a tab into a predetermined raised position on the container, a marking mechanism adjacent said tab raising element and including a fixed anvil jaw and a movable marking jaw mounted adjacent said fixed jaw and readily detachable for replacement with other jaws having other markings for impressing a desired mark on the raised tab of the container, and a heated support for said jaws for heating the jaws while allowing detachment of said movable jaw.

10. In a machine for treating containers having carrying tabs lying flat against a wall of the containers, the combination of a sharp edged blade movable into place against a wall of a container and adjacent its carrying tab for insertion between the container wall and the tab, means operable by said container for actuating the inserted blade to lift the tab into an angular position relative to the container wall, a marking mechanism adjacent said blade, said marking mechanism including a pair of pivoted jaws engageable on both sides of the raised tab for impressing a desired mark on the raised tab, and a swing arm on which said jaws are mounted, 15 said arm being movable relative to the container for swinging said jaws into place one on each side of the raised tab prior to the marking operation and for swinging the jaws away from the container following the marking operation.
- 20 11. In a machine for treating containers having tabs for carrying the containers, the combination of a rotatable turret having spaced pockets for receiving and for advancing containers along a predetermined path of travel, a pusher device operating in time with said turret for inserting a container into a pocket of the turret, a tab raising element adjacent said turret for arranging the tabs on the containers in a predetermined position, a marking mechanism adjacent said tab raising element and operating in 25 time with said turret for impressing a desired mark on the arranged tabs of the advancing containers, holding devices also operating in time with said turret for holding a container against shifting during the marking operation, and discharge means operating in time with the turret for discharging the marked container from the turret to a suitable place of deposit.
